UNITED STATES PATENT OFFICE.

DANIEL KABER, OF CLEVELAND, OHIO.

SIGN.

1,027,547.

Specification of Letters Patent.

Patented May 28, 1912.

Application filed August 11, 1911. Serial No. 643,621.

To all whom it may concern:

Be it known that I, DANIEL KABER, a citizen of the United States, residing at Cleveland, in the county of Cuyahoga and State 5 of Ohio, have invented certain new and useful Improvements in Signs, of which the following is a specification.

This invention relates to improvements in transparent signs, and the main object is to 10 produce an article of this character wherein the sign characters are printed upon one side of a sheet of embossed transparent paper with an offset of the same characters upon the reverse side.

15 The invention also relates to a sign of this character printed with ink treated so that it will take an adhesive substance which when moistened will cause the sign to adhere to the surface of glass without the ink 20 being affected by the moisture.

Referring to the drawings, Figure 1 is a front elevation of a sign arranged according to my invention; and Fig. 2 is a section upon the line 2—2 of Fig. 1.

25 In carrying out the invention I employ a sheet 1 of embossed paper which is provided with an uneven surface and upon the front side of this paper I provide a coating 2 which will indicate the sign characters, and this coating is applied by printing. I also provide a coating 3 on the 30 reverse side registering with the coating on the front side and intensifying its effect.

35 A coating 4 of adhesive material is then applied over the coating 2 to render the sign capable of being applied to glass or

other similar places. The use of an adhesive substance with the ink is practical in no sign except one employing embossed paper, in that after the sign is moistened and placed upon a surface it has no tendency toward shrinkage and the raised portions of the embossed paper prevent the adhesive substance from showing and producing a mottled effect as is always the 45 case when plain paper is used.

There is a great advantage in a sign of this character when made on embossed paper, inasmuch as it breaks up the dead appearance of the background and brings out 50 the color more effectively. The adhesive feature renders the sign practical in that it may be applied to any surface without further gumming or without other attaching means.

Having described my invention, I claim:

A transparent sign comprising a sheet of embossed transparent paper having suitable characters on one side forming a sign, 60 a coating of adhesive substance on said side and over the sign and a coating on the reverse side conforming to the design of the sign character on the front side and in register therewith.

In testimony whereof I affix my signature in presence of two witnesses as follows.

DANIEL KABER.
